SUPPORT FOR MATERIALS

Joseph R. Barlow, Pittsburgh, Pa., assignor of
one-half to Charles X. Wunderly, Pittsburgh,
Pa.

Application January 24, 1942; Serial No. 428,041

20 Claims. (Cl. 211—50)

My invention relates to supports or racks for materials, such as books, magazines, leaflets and newspapers, and has particular relation to the provision of desirable adjustment features therefor.

Many libraries, reading rooms and offices are confronted with the problem of displaying or stacking material, such as noted above, for convenient use. If, as is usually the case, such material is of different sizes, some form of adjustment is very desirable. However, so far as I am aware, I am the first to provide a material-supporting device with adjustments in all three directions to accommodate different lengths, widths and thicknesses of material, such as newspapers, books, magazines and leaflets, thus fully meeting the problem and providing a neat, effective and fully adequate material-supporting device.

One object of my invention, therefore, is to provide a support for material having certain desirable adjustments for the purpose set forth.

Another object of my invention is to provide a support for material comprising a base, together with provision for effecting both sideways adjustments along the base and depth adjustments with respect to the base to accommodate various widths and thicknesses or positions of material.

A further object of my invention is to provide a device of the character set forth above, together with a further provision for effecting up and down adjustments on the base to accommodate various lengths of said material.

A further object of my invention is to provide such depth adjustments in connection with a device having a series of grooves along a vertical side thereof to assist in accommodating various thicknesses of material.

Still another object of my invention is to provide a device of the character set forth including a plurality of sets of pins or the like movable forward and backward with respect to the base at different levels to support material at different distances from the base, thus providing a series of steps for supporting materials at different levels with adjacent materials partially overlapping each other. In this way, a sequence of leaflets, such as monthly editions, may be compactly stacked and still they are readily selectable and replaceable.

Other objects of my invention will become evident from the following detailed description, taken in conjunction with the accompanying drawings, wherein:

Figure 1 is a perspective view of a complete de-

vice or support constructed in accordance with my present invention, with books, leaflets, etc. disposed thereon, the device being mounted on a stand;

5 Fig. 2 is a similar view of the device itself without any such books or leaflets disposed thereon;

Figs. 3 and 4 are, respectively, views in front elevation and rear elevation of the base portion of the material-supporting device of Figs. 1 and 2;

10 Fig. 5 is an end view in plan and Fig. 6 an end view in perspective of the material-supporting device;

Figs. 7 to 12, inclusive, are views of various details of the device;

15 Fig. 13 is another end view in perspective of the material-supporting device; and

Figs. 14 and 15 are views of certain modifications of parts of the device shown in Figs. 1 and 2.

Referring to the drawings, the structure here 20 shown comprises a material-supporting device or rack 1, together with a stand or pedestal 2 therefor.

The device 1 comprises a base 3 having a plurality of transversely-extending internal slots 4, 25 these slots each being provided with two pairs of convex extensions or enlargements 5 in a substantially vertical direction, disposed near the respective ends of each of the slots 4 for a purpose to be set forth, grooved or dovetailed members 6, 6a and 6b being disposed along the top of each of the slots 4 in the rear of the base 3, such members being separated by the convex extensions 5, and similar grooved or dove-tailed members 7, 7a and 7b being disposed on the lower 35 side of each slot 4. It will be understood that the grooves in the members 6 and 7, for example, face each other, so that a sliding member may be moved therewith, as clearly shown in Fig. 6.

Reinforcing blocks 8 and 8a are fastened in a 40 vertical manner to the rear side of the base 3 below each slot 4 and are pierced by a substantially vertically disposed series of small holes 9 which extend from the blocks through the front face of the base 3, for a purpose to be set forth. If 45 desired, a beading or flange 10 may be disposed for ornamental purposes along the rear edges of the base 3.

A plurality of slidable block structures 15, 50 shown in detail in Figs. 10, 11 and 12 and in perspective assembly in Fig. 6, are each provided with a central tongue or projection 16 on the upper side and a similar central tongue or projection 17 on the lower side, these tongues being, respectively, adapted to fit into and slide along the 55 grooves in dovetailed members 6 and 7. In addi-

tion, a large preferably central aperture 18 extends through the block 15 from front to rear for the purpose of receiving another member 20 to be described below, and a plurality (shown as six) of small apertures 13 surrounding said central aperture 18 also extend through the block from front to rear for the purpose of receiving other members 14 to be described below.

A plurality of these slidable block structures 15 are disposed along each slot 4 for the purpose of providing width adjustment for books, etc., and the end structure in each case may be provided with a lateral or end block member 19, as shown in Fig. 1, for the purpose of covering the corresponding end of the slot 4 and providing a more ornamental appearance.

A corresponding plurality of block structures 20, which fit and slide through the large apertures 18 of block structures 15 to provide a backward and forward or depth adjustment, are each provided at their front sides with a thin strip or spacer 21 and may be held in any desired location within the apertures 18 by means of a bent strip spring 22 attached to the upper side of each block structure 20 by means of a screw 23, for example.

The strip or spacer 21 thus acts as a stop with respect to the backward movement of block structure 20 and at the same time engages the material to be supported along one side thereof.

To provide lengthwise adjustment for the books, magazines, etc., a plurality of shelves or ledges 27, which are respectively provided with a series of dowel pins or the like 30, are adapted to be set at various vertical heights at two different levels, as illustrated in Fig. 1, along the face of base 3 by reason of disposing the dowel pins in the proper sets of small holes 9 in the base 3.

In addition, a pair of vertically spaced relatively narrow shelves or ledges 28 and 29 is disposed below the shelf 27 at each of the two levels illustrated, being likewise movable up or down as desired or readily removable by reason of the provision of dowel pins 31 and 32 like dowel pins 30 in the case of the shelves 27.

If desired, a plurality of beads or flanges extending upwardly or downwardly or both from the front edges of the shelves 27, 28 and 29 may be provided, being indicated by the reference characters 33, 34 and 35, respectively.

The width of the ledges or shelves 28 and 29 inside of the beads or flanges 34 and 35, respectively, is substantially the same as the width of notch 25 on the inner under side of shelf 27. The notch 25 and the upper side of shelf 28, on the one hand, and also the under side of shelf 28 and the top side of shelf 29, on the other hand, may thus be utilized for carrying signs or information strips when desired, such material being readily sidable in and out of place, as will be appreciated.

Each of the block structures 15 is preferably provided, in addition to the large central aperture 18, with a plurality of small holes or apertures 13, in this case six apertures, disposed in horizontal pairs at three different levels on each side of the central aperture 18, as clearly shown in Figs. 10 and 12, for example. It will be noted that the three levels on each block structure 15 correspond, so that three long horizontal rows of pins 14 may be provided along each slot 4 in base 3.

Each of these small apertures 13 is adapted to receive a pin or small rod 14 which may be provided with a head 26 of any desired shape, and

the rear end of each pin, after the pin is inserted through the corresponding hole 13, may be bent at substantially right angles, as shown. The purpose of the head 26, shown as a single vertical member attached at substantially its mid point to the body of the pin, is to serve as a flange, when the body of the pin is used as a shelf, to prevent material from slipping forwardly off the pin and, at the same time, the head 26 may be utilized as a handle for moving the pin forwardly and backwardly through the corresponding hole 13 to dispose the head of the pin at a selected distance in front of the base.

The purpose of the bent rear end of each pin is to prevent the pin from being accidentally withdrawn through the hole 13 as the pin is adjusted forwardly or backwardly.

The device 1 may be assembled as follows: A suitable number, shown in Figs. 1 and 2 as five, of the block structures 15 are inserted in place along each slot 4 by slipping them diagonally through the convex extensions or enlargements 5 of the slots 4 into a position where the central tongues 16 and 17 are respectively disposed in the grooves of dovetailed members 6 and 7, respectively, as clearly shown in Fig. 6. The three central block structures are of the type shown in Fig. 12, for example, while the two end block structures are of a similar character, plus the addition of the side blocks 19 for a purpose already described. The various pins 14 may then be placed in the holes 13 of block structures 15, as previously described.

One of the block structures 20 is then slid backwardly through the large aperture 18 in each of the block structures 15, and the ledges or shelves 27, 28 and 29 are then placed on base 3 at desired vertical intervals by means of the illustrated dowel pin connection.

A number of books, magazines, etc. may then be disposed in place, as illustrated in Fig. 1, the block structures 15 being slid sideways in either direction to accommodate the width of such material, the block structures 20 being moved forwardly or backwardly to accommodate various depths or thicknesses of such material, while one or both of the horizontal shelves or ledges 27 may be moved up or down to the desired vertical position (on one or both of the illustrated levels) to accommodate different lengths of such material. Of course, if desired, the ledges 28 and 29, one or both, at either level, may be removed to permit placing the corresponding shelf 27 at a lower level than would otherwise be possible.

As will be noted particularly from Fig. 13, the pins 14 in each of the block structures 15 may be moved by means of the heads 26 to any desired position or distance in front of the base 3. In Fig. 13, the top pair or row of pins 14 is advanced a sufficient distance so that a magazine or leaflet, such as 39, may be placed on end supported by one pin 14 near the upper right-hand corner of a block structure 15, and another pin 14 near the upper left-hand corner of the next adjacent block structure 15 on the right.

In this way, the two pins, one in each of adjacent block structures, serve as a horizontal shelf or support for a magazine or leaflet, and the heads 26 of the pins prevent such magazine or leaflet from slipping forwardly off the pins.

The next lower pair of pins 14 may be advanced to a greater distance in front of the base 3 and the lower pair of pins may be advanced a still greater distance in front of the base, as illus-

trated in Fig. 13. As a result, other magazines or leaflets 39a and 39b may be placed on the corresponding pairs of pins, one in each of the adjacent block structures 15 and, in addition, a magazine or leaflet 39c may be placed to rest on shelf 27 near the outer flange 33 thereof.

In this way, it will be noted that a series or sequence of leaflets or magazines, such as monthly issues, may be placed on the pairs of pins in question and the shelf 27 in such manner that the pins and shelf provide a series of steps for supporting the magazines, leaflets or other materials at different levels with adjacent materials partially overlapping each other. In this way, the date of issue of each such magazine, which is usually displayed near the top thereof, may be readily ascertained and at the same time a considerable number of magazines or leaflets may be stacked in such manner as to require a minimum of vertical space.

It will be appreciated that, if desired, in any one section of my illustrated material support, the rows or pairs of pins 14 may be utilized as shown in Fig. 13 to support different sets of magazines or leaflets in stepped sequence or, if desired, one such set of magazines may be stacked as illustrated in Fig. 13, and the pins 14 on the left-hand side of the illustrated left-hand block structure 15 may be pushed in or backwardly until the heads 26 engage the front surface of that block structure 15, after which the corresponding block structure 20, which is slideable in and out of the central large aperture 18, may be utilized to engage and hold one side of another magazine or leaflet, as illustrated in Fig. 1, for example.

In this way, by suitable positioning of the block structures 15 and 20, the shelves 27, and pins 14, any material, regardless of its length, width or thickness, from a newspaper, for example, to a small book, may be accommodated by reason of the sideways, front and back and vertical adjustments described above, while at the same time, in the case of such books, magazines, leaflets, etc., the neighboring or adjacent material may be of a different size and still be properly accommodated by the proper placing of the various illustrated adjusting structures and shelves, and a stepped sequence of material may also be provided.

For example, by pushing in or removing all but the outer block structures 15 and 20, a newspaper may be properly accommodated by resting it on one of the ledges such as the lower ledge 27 and adjusting the outer block structures 15 and 20 to properly hold the newspaper. Smaller material, such as leaflets, magazines and books, may be properly accommodated by placing and adjusting a proper number of the illustrated adjustable structures 15, 20 and 27 and pins 14, as will be understood.

The device or support so far described may be hung on a wall or placed on the stand or pedestal 2, as illustrated. The pedestal 2 is shown as comprising a bottom support 50 which may have a downwardly-sloping face 51 on which a shelf or ledge 52 may be provided for supporting books 53 or the like. A suitable horizontal block 54 may be disposed on the rear upper surface of support 50, and a plurality of vertical supporting members 55 and 56 may extend from the block 54 to the rear side of base 3.

However, it will be understood that any other suitable means for supporting or mounting the

material-supporting device 1 may be employed if desired.

In lieu of the block structure 20 previously described, a modification thereof shown in Figs. 14 and 15 may be utilized. This block structure comprises a main body or block member 40 having a grooved or otherwise decorated strip or plate 41 attached to the front side thereof, and the upper side of member 40 may be provided with a spring strip 42 held in position by a screw 43, for example. This spring strip serves the same frictional holding purpose as previously described in connection with spring strip 22.

Each vertical side of the member 40 may be provided with a series of grooves 44, 45 and 46, for example, thus assisting, as the block structure is moved forwardly and backwardly, in accommodating books, leaflets, etc. of different thicknesses. The pins 14 and small apertures 13 may be employed as previously described in connection with block structures 15.

For the purpose of preventing accidental forward withdrawal of a block structure 20 or 40, a turn button 38 (see Fig. 9) is used at the rear of such block structure. This turn button may be of any suitable form, having its length greater than its width, pivoted on the corresponding block structure.

It will be noted that by disposing the turn button 38 with its longer dimension in a substantially vertical direction, the block structure 20 or 40 may be readily inserted or withdrawn, whereas if the turn button 38 has its longer dimension disposed in a substantially horizontal position, then such disposition will prevent the accidental forward withdrawal of the block structure 20 or 40, as such button will engage the sliding block structure 15. It will be seen, therefore, that I have provided a relatively simple but effective support for materials, such as books, magazines, leaflets and newspapers, which provides ready and effective adjustment in sideways, vertical and backward and forward directions and in which various parts may be readily moved or removed to accommodate various sizes and positions of such material.

I do not wish to be restricted to the specific structural details or arrangement of parts herein set forth as various other modifications thereon may be effected within the spirit and scope of my invention. I desire, therefore, that only such limitations shall be imposed thereon as are indicated in the appended claims.

I claim as my invention:

1. A support for material comprising a base, means for effecting sideways adjustment along said base to accommodate various widths of said material, and second means cooperating with and movable beyond said first means for effecting depth adjustments with respect to said base to accommodate various thicknesses of said material.

2. A support for material comprising a base having a sideways extending opening therein, means slideable along said opening to accommodate various widths of said material, and second means slideable through said first means for effecting depth adjustments with respect to said base to accommodate various thicknesses or positions of said material.

3. A support for material comprising a base having a sideways extending opening therein, means having an aperture extending from front to rear and also having a tongue-and-groove connection with said base slideable along said

opening to accommodate various widths of said material, and second means slidable forward and backward through said aperture for effecting depth adjustments with respect to said base to accommodate various thicknesses of said material.

4. A support for material comprising a base having a sideways extending opening therein, means having an aperture extending from front to rear and also having a tongue-and-groove connection with a rear portion of said base, said means being slidable along said opening to accommodate various widths of said material, and second means slidable backward and forward through said aperture for effecting depth adjustments with respect to said base to accommodate various thicknesses of said material.

5. A support for material comprising a base having a sideways extending opening therein, means having an aperture extending from front to rear and also having a tongue-and-groove connection with said base slidable along said opening to accommodate various widths of said material, and second means slidable forward and backward through said aperture for effecting depth adjustments with respect to said base to accommodate various thicknesses of said material, said second means having a member disposed in front of said base to act as a stop with respect to the backward movement thereof and to also engage said material along one side.

6. A support for material comprising a base having a sideways extending opening therein, means having an aperture extending from front to rear and also having a tongue-and-groove connection with a rear portion of said base, said means being slidable along said opening to accommodate various widths of said material, and second means slidable backward and forward through said aperture for effecting depth adjustments with respect to said base to accommodate various thicknesses of said material, said second means having a member disposed in front of said base to act as a stop with respect to the backward movement thereof and to also engage said material along one side.

7. A support for material comprising a base, means for effecting sideways adjustment along said base to accommodate various widths of said material, second means cooperating with and movable beyond said first means for effecting depth adjustments with respect to said base to accommodate various thicknesses of said material, and third means cooperating with said other means for effecting up-and-down adjustments on said base to accommodate various lengths of said material.

8. A support for material comprising a base having a sideways extending opening therein, means slidable along said opening to accommodate various widths of said material, second means slidable with respect to said first means for effecting depth adjustments with respect to said base to accommodate various thicknesses of said material, and third means cooperating with said other means for effecting up-and-down adjustments on said base to accommodate various lengths of said material.

9. A support for material comprising a base having a sideways extending opening therein, means having an aperture extending from front to rear and also having a tongue-and-groove connection with said base slidable along said opening to accommodate various widths of said material, second means slidable forward and

backward through said aperture for effecting depth adjustments with respect to said base to accommodate various thicknesses of said material, and third means engageable on said base at different levels to accommodate various lengths of said material.

10. A support for material comprising a base having a sideways extending opening therein, means having an aperture extending from front to rear and also having a tongue-and-groove connection with a rear portion of said base, said means being slidable along said opening to accommodate various widths of said material, second means slidable backward and forward through said aperture for effecting depth adjustments with respect to said base to accommodate various thicknesses of said material, and third means adapted for pin-and-hole engagement at different levels on said base to accommodate various lengths of said material.

11. A support for material comprising a base having a sideways extending opening therein, means having an aperture extending from front to rear and also having a tongue-and-groove connection with said base slidable along said opening to accommodate various widths of said material, second means slidable forward and backward through said aperture for effecting depth adjustments with respect to said base to accommodate various thicknesses of said material, said second means having a member disposed in front of said base to act as a stop with respect to the backward movement thereof and to also engage said material along one side, and third means adapted for pin-and-hole engagement at different levels on said base to accommodate various lengths of said material.

12. A support for material comprising a base having a sideways extending opening therein, means having an aperture extending from front to rear and also having a tongue-and-groove connection with a rear portion of said base, said means being slidable along said opening to accommodate various widths of said material, second means slidable backward and forward through said aperture for effecting depth adjustments with respect to said base to accommodate various thicknesses of said material, said second means having a member disposed in front of said base to act as a stop with respect to the backward movement thereof and to also engage said material along one side, and third means adapted for pin-and-hole engagement at different levels on said base to accommodate various lengths of said material.

13. A support for material comprising a base having a sideways extending opening therein, means slidable along said opening to accommodate various widths of said material, and second means slidable with respect to said first means for effecting depth adjustments with respect to said base to accommodate various thicknesses of said material, said second means having a series of grooves along a vertical side to assist in accommodating such various thicknesses of material.

14. A support for material comprising a base having a sideways extending opening therein, means having an aperture extending from front to rear and also having a tongue-and-groove connection with said base slidable along said opening to accommodate various widths of said material, and second means slidable forward and backward through said aperture for effecting depth adjustments with respect to said base to

accommodate various thicknesses of said material, said second means having a series of grooves along a vertical side to assist in accommodating such various thicknesses of material.

15. A support for material comprising a base having a sideways extending opening therein, means having an aperture extending from front to rear and also having a tongue-and-groove connection with a rear portion of said base, said means being slideable along said opening to accommodate various widths of said material, and second means slideable backward and forward through said aperture for effecting depth adjustments with respect to said base to accommodate various thicknesses of said material, said second means having a series of grooves along a vertical side to assist in accommodating such various thicknesses of material.

16. A support for material comprising a base having a sideways extending opening therein, means slideable along said opening to accommodate various widths of said material, and a plurality of means supported by and movable forward and backward with respect to said first means to support material at different distances from said base.

17. A support for material comprising a base having a sideways extending opening therein, means having a plurality of apertures extending from front to rear and also having a tongue-and-groove connection with said base slideable along said opening to accommodate various widths of said material, and a plurality of second means slideable forward and backward through said apertures to support material at different distances from said base.

18. A support for material comprising a base having a sideways extending opening therein, means having a plurality of sets of apertures extending from front to rear at different levels and also having a tongue-and-groove connection with a rear portion of said base, said means being slideable along said opening to accommodate various widths of said material, a plurality of sets of second means slideable backward and forward 45 through said sets of apertures and adjustable to

project different distances from said base to provide a series of steps for supporting materials at different levels with adjacent materials partially overlapping each other.

19. A support for material comprising a base having a sideways extending opening therein, means having a large aperture and a plurality of small apertures extending from front to rear, the small apertures at different levels, and also 10 having a tongue-and-groove connection with said base slideable along said opening to accommodate various widths of said material, second means slideable forward and backward through said large aperture for effecting depth adjustments with respect to said base to accommodate various 15 thicknesses of said material, and a plurality of third means slideable forward and backward through said small apertures and adjustable to project different distances from said base to provide a series of steps for supporting materials at different levels with adjacent materials partially overlapping each other.

20. A support for material comprising a base having a sideways extending opening therein, 25 means having a large central aperture and a plurality of small apertures surrounding said large aperture extending from front to rear, the small apertures at different levels, and also having a tongue-and-groove connection with a rear portion of said base, said means being slideable along 30 said opening to accommodate various widths of said material, second means slideable backward and forward through said large aperture for effecting depth adjustments with respect to said 35 base to accommodate various thicknesses of said material, and a plurality of third means slideable forward and backward through said small apertures and adjustable to project different distances from said base to provide a series of steps for supporting materials at different levels with adjacent materials partially overlapping each other from front to back.

JOSEPH R. BARLOW.
